US0D1002579S

(12) **United States Design Patent** (10) Patent No.: **US D1,002,579 S**
(45) Date of Patent: ** Oct. 24, 2023

(54) **ELECTRONIC DEVICE**

(71) Applicant: **Amazon Technologies, Inc.**, Seattle, WA (US)

(72) Inventors: **Michael Edward James Paterson**, Lafayette, CA (US); **Giles David Matthew McWilliam**, San Francisco, CA (US)

(73) Assignee: **Amazon Technologies, Inc.**, Seattle, WA (US)

(**) Term: **15 Years**

(21) Appl. No.: **29/837,329**

(22) Filed: **May 4, 2022**

Related U.S. Application Data

(62) Division of application No. 29/670,239, filed on Nov. 14, 2018, now Pat. No. Des. 954,681.

CLAIM

The ornamental design for an electronic device, as shown and described.

DESCRIPTION

FIG. 1 is a top perspective view of an electronic device; FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the electronic device that form no part of the claimed design. The dot-dashed broken lines represent boundaries of the claimed electronic device and form no part of the claimed design.

1 Claim, 7 Drawing Sheets
